UNITED STATES PATENT OFFICE.

WILLIAM E. BROWN, OF COALINGA, CALIFORNIA.

FULL-ROD GUIDE.

Application filed August 23, 1926. Serial No. 130,941.

This invention relates to deep well pumping apparatus and particularly pertains to guide means for guiding the pull rods of central power plant installations.

As is well known, it is the practice in low producing oil fields to provide a single power plant for a group of adjacent wells. This power plant is connected with the pumping jack of each well by a cable commonly termed a pull rod. In some instances the wells are located at a considerable distance from the power plant, necessitating the provision of some guide means for properly supporting and guiding the pull rod. Prior to my invention blocks of wood were arranged on upright supports over which the pull rod was led. Due to dust and other gritty substances accumulating on this support, considerable friction resulted and consequently caused a loss in efficiency of the plant.

It is the principal object of the present invention to provide a pull rod guide of simple and inexpensive construction and where- in the friction losses will be negligible.

In carrying out this object into practice I provide a bearing adapted to be supported in an upright position and upon which the pull rod may bear. This bearing is so constructed that the wear on the pull rod and bearing will be minimized.

One form which the invention may assume is exemplified in the following description and illustrated by way of example in the accompanying drawings, in which:

Fig. 1 is a front elevation of a bearing embodying the preferred form of my invention.

Fig. 2 is a vertical section taken on line II—II of Fig. 1.

Fig. 3 is a front elevation of a bearing embodying a slight modification of the invention.

Referring more particularly to the accompanying drawings, I show an upright support 10 which may be arranged at intermediate points between the power plant and the well. In Fig. 1 this support is shown as a pipe, whereas in Fig. 3 it is disclosed as a post.

Reference being had to Fig. 1 it is seen that at the top of the support 10 a bearing 11 is provided. The lower end of this bearing 11 is cylindrical and is provided with a downwardly projecting shank 12 of reduced diameter. The diameter of this shank

12 agrees with the interior diameter of the support 10 so that it may be projected therin and securely bolted or otherwise fastened to the support.

The upper end of the bearing member 11 is substantially U-shaped and is formed with a socket 14 which extends downwardly from its upper end intermediate the side walls of the bearing. This socket 14 is substantially rectangular and is adapted to snugly receive a bearing plate 15, which agrees in size and configuration with the socket 14. This bearing plate 15 is flat as disclosed in the drawings, and its upper and lower ends are recessed to accommodate the pull rod indicated by the numeral 16. The recesses in the ends of the bearing are located substantially at the center of the bearing plate as disclosed. These recesses are slightly larger than the pull rod so that the latter may freely reciprocate therethrough, while bearing on the lower surfaces of the recesses.

At the center of the recess at each end of the bearing, a small pocket 16a is formed, which may be packed with graphite or other lubricant. The lubricant in these pockets will readily transfer to the pull rod to lubricate the bearing surfaces between it and the bearing plate 15.

It is intended that the bearing plate 15 be of lignum vitae or other anti-friction material having good wearing qualities. The purpose of forming recesses in both the upper and lower ends of the bearing plate 15 is that when one end becomes worn, the bearing plate may be removed from the bearing block and inverted to provide a second or new bearing surface. When both ends become worn the bearing plate 15 may be removed and discarded, and a new one substituted therefor, thus, keeping the cost of upkeep of the apparatus at a minimum.

In Fig. 3 the only difference between the device disclosed there and that disclosed in Fig. 1 is that the bearing 11 may be connected to the side of a square post or upright. This is desirable in certain installations where two or more pull rods extend in the same directions at different levels. Thus, one post may support one or more bearings.

In operation of the device the uprights 10 are located at spaced distances between the power plant and the pumping jack with the bearing 11 disposed substantially at right angles to the line of pull of the rods. Lubri-

cant, such as graphite, is then packed in the pocket 16° and the pull rod is extended through the recesses in the bearing plate 15. As the bearing plate is comparatively thin, the bearing surface between it and the pull rod is small, reducing the friction therebetween. When one end of the bearing plate 15 becomes worn, it may be reversed to present a new bearing surface to the pull rod. When both ends become worn, the bearing plate 15 may be removed and discarded and a new bearing plate inserted in the bearing 11. As these bearing plates are comparatively inexpensive in construction, the cost 15 of upkeep of the apparatus will be comparatively small.

While I have shown the preferred form of my invention, it is to be understood that various changes may be made in its construction by those skilled in the art, without departing from the spirit of the invention, as defined in the appended claims.

Having thus described my invention, what I claim and desire to secure by Letters 25 Patent is:

1. A device of the character described comprising a bearing adapted to be arranged upon an upright support, said bearing having a socket formed inwardly from the upper 30 end thereof, a bearing plate adapted to fit within said socket, the opposite ends of said bearing plate being recessed, one recessed end being presented and upon which a pull rod may bear and reciprocate.

2. A device of the character described comprising a bearing adapted to be arranged upon an upright support, said bearing having a socket formed inwardly from the upper 35 end thereof, a bearing plate adapted to fit within said socket, the opposite ends of said bearing plate being recessed, one recessed

end being presented and upon which a pull rod may bear and reciprocate, and a lubricant pocket formed in said bearing plate in communication with said recesses for distributing lubricant to the pull rod. 45

3. A device of the character described comprising a bearing adapted to be arranged on an upright support, the upper end of said bearing being substantially U-shaped, a 50 socket formed in said bearing and extending downwardly from the upper end and between the side walls of the bearing, a bearing plate of a size and configuration agreeing with said socket and adapted to be removably inserted therein, the opposite ends of said bearing plate being recessed to accommodate a pull rod, and a lubricant pocket at the center and inner extremity of each recess. 55

4. A device of the character described comprising a hollow upright support, a bearing, a downwardly extending shank on the bearing adapted to be projected within the upper end of said support to support the bearing on said support, said bearing having a substantially flat upper end adapted to be arranged at right angles to a pull rod to be supported thereon, said upper end of the bearing being substantially U-shaped 70 and having a socket extending downwardly from the upper end thereof between its side walls, a flat bearing plate of a size and configuration agreeing with said socket and adapted to be removably inserted in said socket, the opposite ends of said bearing being recessed to accommodate a pull rod, and a lubricant pocket in communication with each recess to lubricate the pull rod as it bears on the bearing plate. 75

WILLIAM E. BROWN.
